PROCESS FOR MAKING FIBROUS BRISTLES

John Overbeke, Cleveland Heights, Ohio

Application February 3, 1942, Serial No. 429,405

3 Claims. (Cl. 117—4)

1

My invention relates in general to the process for impregnating a fibrous cord and more particularly to a process for making impregnated bristles for brushes and the like.

An impregnated cord produced by my apparatus and process is suitable for brushes for industrial purposes or the like. The impregnated cord is relatively thin and is capable of withstanding a terrific amount of severe abuse in the polishing and surfacing of metals and other materials requiring polishing and surfacing. The impregnated cord is thus used for bristles in brushes and the like.

In the practice of my invention, the cord is impregnated with glue or any other suitable viscous substance. The glue or other viscous substance may have finely divided abrasive material therein to produce a more vigorous polishing or surfacing action upon the metal or other substance being processed. Thus, for example, the glue or other viscous substance may have finely divided abrasive materials in the nature of powder or in larger particles so long as the abrasive material is capable of remaining in suspension in the glue or other viscous substance during the process of impregnating the cord with the glue. As used herein, the term "glue or other viscous substance" is interpreted to include the abrasive material or substance therein. Also as used herein, the term glue or viscous glue is meant any viscous liquid which when soaked into the cord will act as an impregnating and therefore a binding medium for anchoring the strands of the cord.

In the impregnation of a cord with glue or other viscous substance, a great deal of difficulty has been experienced in forcibly causing the glue or other viscous substance to penetrate the cord and completely fill the interstices of the cord to render the cord uniform. In using a fibrous impregnated cord as the bristle for a brush, it is essential that the bristles be uniformly impregnated throughout their length because if non-uniformity exists in the impregnation of the cord, some of the bristles will wear away sooner than others leaving the brush in poor condition to do a good polishing or surfacing operation.

An object of my invention is the process of impregnating a fibrous cord with glue or other viscous substance so that the impregnation is thoroughly uniform throughout the length of the cord or bristle.

Another object of my invention is to provide for impregnating a roll of fibrous cord with vis-

2

cous glue by unwinding the cord from the roll with the roll revolving in the glue.

Another object of my invention is to provide for relieving as much as possible the tension upon the impregnated cord as it is wound upon the take-up reel.

Another object of my invention is to provide for separating the layers of impregnated cord on the take-up reel by removing the cord from the take-up reel and re-winding it upon a severing reel where the layers of cord are cut in suitable lengths for brush bristles.

Another object of my invention is to provide for drying the impregnated cord after it has been once cut up in bristles.

Another object of my invention is the provision of thoroughly impregnating a fibrous cord with viscous glue or other viscous substances without the use of rollers forcing the glue into the cord or without the use of a vacuum to force the glue into the cord.

Other objects and a fuller understanding of my invention may be had by referring to the following description and claims, taken in conjunction with the accompanying drawing, in which:

Figure 1 represents a diagrammatic side elevational view of my apparatus for carrying out the process of impregnating the cord with viscous glue or other viscous material in accordance with my invention;

Figure 2 is a perspective view of the equipment shown in Figure 1; with a modification in the directional reversing roll;

Figure 3 is a diagrammatic illustration of a side elevational view of a take-up reel and a severing reel employed in carrying out my process;

Figure 4 is a plan elevational view of the equipment shown in Figure 3;

Figure 5 illustrates a group of the impregnated layers of cord;

Figure 6 shows a perspective view of a roll of fibrous material which is adapted to be impregnated in accordance with my process;

Figure 7 is a side elevational view of the glue vessel employed in my process and showing the disposition of the rolls of fibrous cord therein during the impregnation thereof;

Figure 8 shows a side elevational view of a revolving drying wheel employed to dry the group of impregnated cord as shown in Figure 5; and

Figure 9 is an end view of the revolving drying wheel shown in Figure 8.

With reference to Figures 1, 2 and 7, I illustrate a process and apparatus for impregnating a fibrous cord 11 with viscous glue or other viscous

substance contained in a glue vessel 12. The cord 11 is unwound from a roll of fibrous cord illustrated by the reference character 10. In the practice of my invention I may employ a single roll 10 or a plurality of rolls. In Figure 2 I illustrate 8 rolls of fibrous cord disposed in the glue vessel 12. In the practice of my invention the cord 11 is unwound from the rolls 10 with the rolls revolving in the glue contained in the glue vessel. In the drawing, I illustrate the rolls of fibrous cord 10 being completely immersed below the level of the glue indicated by the reference character 13. The cords 11 as they are unwound from the rolls 10 pass over a roller 14 suitably supported upon the upper edge of the glue vessel 12. As illustrated in Figure 6, each of the rolls of fibrous cord is carried by a roll holding device 15 which may be adjustably fastened to cross bars 17 supported on top of the glue vessel 12. The roll holding devices 15 may be adjustable in a vertical manner by any suitable means and as illustrated I employ a wing nut 16 which may be manually turned for making the adjustment or for mounting a new roll in the glue vessel 12. The rolls of fibrous cord are preferably wound with a space between the adjacent layers of the cord so that the glue may gradually soak itself easily into the roll. In this manner the glue is given a relatively long period of time in which to soak into the cord before the cord passes out of the glue vessel 12. In the practice of my invention I preferably immerse the entire roll of cord below the level of the glue but I find that satisfactory results may be obtained if the roll is not entirely immersed because the roll revolves as the cord is withdrawn therefrom. Thus, the layers of the cord upon the roll are soaked with glue long prior to the time that the last layer or outside layer is withdrawn from the roll. Another advantage of withdrawing the cord with the roll revolving in the glue is that I do not need to employ rollers to force the glue into the cord and accordingly I obviate the requirement of putting a great deal of tension upon the cord as it is removed from the glue vessel. In addition, the revolving rolls agitate the glue and keep the consistency uniform.

As shown in Figures 1 and 2, after the cord leaves the glue vessel 12 it passes through a glue setting device indicated by the reference character 20 which may comprise rubber-like or sponge-like material through which the impregnated cords pass as a suitable liquid of glue setting characteristic is pumped upon the rubber-like or sponge-like material from a tank 21 by means of a pump 22 and a pipe 23. By the circulating arrangement as illustrated, the rubber-like or sponge-like material through which the impregnated cord passes is always maintained in a wet condition with the glue setting liquid.

After the cords of impregnated fibrous material pass through the glue setting device, they are then directed to a reversing drive roller means carried by a support 26 and driven by an electric motor or other suitable drive 25. The reversing drive roller means may comprise a single drive roller 24 as shown in Figure 2 or double drive rollers 24 and 27 as shown in Figure 1. The arrangement of Figure 1 is preferable as the glue setting liquid is given an opportunity to trickle down the vertical cord between the two rollers 27 and 24 which greatly facilitates the drying of the cord. That is to say, any excess glue setting liquid on the cord is caused to drain off the cord before it passes over the roll 27. The

impregnated cords pass from the reversing drive roller means to a take-up reel 29 carried by a support 31 and driven by a motor 30. As diagrammatically illustrated, the motor 30 also reciprocally drives a guide 33 by a transmitting movement illustrated diagrammatically by the dash-dot line 34. The guide 33 as it oscillates back and forth provides for directing the cords of the impregnated material upon the take-up reel 39 to give substantially a level wind. The guide 33 preferably is designed to make one traverse for each revolution of the wheel to make a criss-cross wind to keep the cords from sticking together as much as possible.

The impregnated cords as they pass around the driving roller means are sticky and thus the driving roller means provides for withdrawing the cords from the glue vessel and through the glue setting device 20. Consequently, the take-up reel 29 is relieved of providing the necessary pull to withdraw the cords from the glue vessel 12 and from drawing the impregnated cords through the glue setting device. In other words, the tension of the cords as they are wound upon the take-up reel is relatively slight being only that required to take up the slack between the reversing drive roller means and the take-up reel 29. This is an important feature in that the impregnated cords are not wound tightly about the take-up reel which would tend to make the cords stick together as they dry. An air drying chamber 25 may be employed to hasten the drying of the glue. As illustrated in Figure 1, the impregnated cord is arranged to pass through the air drying chamber 35 as it leaves the glue vessel 12 and prior to reaching the glue setting device 20 and the cord as it returns from the reversing drive roller 27 may also again pass through the air drying chamber 35 before being wound upon the take-up reel 29. Care must be exercised that the air drying chamber does not dry the glue too quickly as it may tend to destroy the beneficial results of the glue impregnated in the fibrous cord for bristle purposes.

After the cords are wound upon the take-up reel 29 they are permitted to dry in atmosphere until they have dried sufficiently so that they no longer stick together when they are separated. I provide for separating the layers of cord on the take-up reel 29 by removing the cord from the take-up reel and re-winding it upon a severing reel 37. This is illustrated in Figures 3 and 4. The support 31 for the take-up reel 29 is provided with casters 32 so that the take-up reel 29 may be rolled over in alignment with the severing reel 37. While the take-up reel 29 is being unwound as shown in Figures 3 and 4 a spare take-up reel 29 may be used to carry out the process in Figures 1 and 2 while the processes in Figures 3 and 4 are likewise being carried out. The severing reel is supported by a support 38 and may be driven by a motor 39 which also operates a guide 42 for directing the cords upon the severing reel 37. The motor 39 may drive the guide in any suitable manner and as illustrated it may be oscillated back and forth by means of a transmitting movement indicated by the dash-dot line 36. As shown in Figure 4, the severing reel 37 is provided with two halves 40 and 41 upon which the impregnated cords may be wound. The cord is first wound upon one-half such, for example, as the half 41 until the reel is substantially full and then the layers of cord are tied at intervals by the tying cord 43. After one-half is filled then the other half, for

example, 40 is then wound until it is full, and then this half is likewise tied at intervals by a tying cord. When both halves are filled and properly tied, then the layers of cord are severed near the places where the tying cords are located. The severing of the layers of cord produce groups of impregnated cord as illustrated by the reference character 44 in Figure 5. The impregnated cords in the groups of impregnated cord do not stick together as they have been separated when the cords are unwound from the take-up reel 29 and wound upon the severing reel 37. The groups of impregnated cord 44 may be suspended from a suitable hook in a drying room where the impregnated cords are further allowed to dry or they may be dried in a quicker fashion by a revolving drying wheel indicated by the reference character 47 carried by a support 48, see Figures 8 and 9. The revolving drying wheel is provided with a series of peripherally arranged screen compartments 50 to receive the groups of impregnated cord 44. Each of the screen compartments 50 is provided with a hinged screen cover 51, so that the groups of impregnated cord may be readily placed in the screen compartments of the revolving drying wheel by merely opening the hinged screen cover and placing the groups of impregnated cord longitudinally cross-wise therein. The revolving drying wheel 47 may be revolved by a motor 49 which readily hastens the drying of the impregnated cords.

As shown in Figure 7, the bottom corners of the glue vessel 12 are round so that the rolls of fibrous material may be arranged to revolve relatively close thereto as the cord 11 is withdrawn therefrom. The revolving of the rolls 10 relatively close to the round corners keeps the glue or other viscous substance which may have finally divided abrasive material therein from collecting in the corners as it would do if the corners of the glue vessel were square. The glue vessel 12 is preferably made with a water or steam jacket and the heat is applied to the outside of the water or steam jacket. In the drawing the steam jacket is not shown but the heat is applied as indicated by the arrows which include heating methods of all kinds.

Although I have described my invention with a certain degree of particularity, it is understood that the present disclosure has been made only

by way of example and that numerous changes in the details of construction and the combination and arrangement of parts may be resorted to without departing from the spirit and the scope of the invention as hereinafter claimed.

5 I claim as my invention:

1. The process of impregnating a fibrous cord with viscous glue comprising the steps of winding the cord in a wound roll with space between adjacent turns so that the glue may penetrate the wound roll between adjacent turns when the roll is placed in the glue, soaking the wound roll of the fibrous cord in the viscous glue and thereby allowing the glue to penetrate the turns of the cord prior to the time that the cord is withdrawn from the roll, withdrawing the soaked cord from the roll at a point below the level of the glue while the roll remains in the glue, and revolving the roll as it is withdrawn to keep the glue well agitated around the roll.
- 10 2. The process of impregnating a fibrous cord with viscous glue comprising the steps of winding the cord in a wound roll with space between adjacent turns so that the glue may penetrate the wound roll between adjacent turns when the roll is placed in the glue, soaking the wound roll of the fibrous cord in the viscous glue and thereby allowing the glue to penetrate the turns of the cord prior to the time that the cord is withdrawn from the roll, withdrawing the soaked cord from the roll while the roll remains in the glue, and agitating the glue around the roll as the cord is withdrawn.
- 15 3. The process of producing a fibrous bristle for brushes comprising the steps of impregnating a fibrous cord with viscous glue by winding the cord in a wound roll with space between adjacent turns so that the glue may penetrate the wound roll between adjacent turns when the roll is placed in the glue, soaking the wound roll of the fibrous cord in the viscous glue and thereby allowing the glue to penetrate the turns of the cord prior to the time that the cord is withdrawn from the roll, withdrawing the soaked cord from the roll while the roll remains in the glue and agitating the glue around the roll as the cord is withdrawn, passing the unwound cord through a glue setting device, and then severing the impregnated cord at intervals to make the bristles.

40 45 50 JOHN OVERBEKE.
